UNITED STATES PATENT OFFICE.

MARTIN M. PERKINS, OF ALABAMA CITY, ALABAMA.

COTTON-CHOPPER.

1,112,029.

Specification of Letters Patent. Patented Sept. 29, 1914.

Application filed May 19, 1914. Serial No. 839,546.

To all whom it may concern:

Be it known that I, MARTIN M. PERKINS, a citizen of the United States, residing at Alabama City, in the county of Etowah and 5 State of Alabama, have invented a new and useful Cotton-Chopper, of which the following is a specification.

This invention relates to cotton choppers, one of its objects being to provide a structure of this character which can be adjusted to different widths and which utilizes a chopping element mounted for oscillation, there being means revoluble with the supporting wheels of the structure whereby the 15 actuation of the chopping element is effected during the forward movement of the machine.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, can be made within the scope of what is claimed, without departing from the spirit of the invention.

In the accompanying drawings the preferred form of the invention has been shown. 30 In said drawings: Figure 1 is a plan view of the machine. Fig. 2 is an enlarged rear elevation thereof. Fig. 3 is a detail view of the chopper. Fig. 4 is a perspective view of the adjustable connection between the side 35 beams. Fig. 5 is a detail view of one of the bearings of the chopper shaft. Fig. 6 is a detail view of two of the tappets and a portion of the shaft carrying the same.

Referring to the figures by characters of 40 reference 1 designates supporting wheels carrying an axle 2 which supports parallel side beams 3. These beams are provided, at their front ends, with draft strips 4 preferably formed of straps of metal, the forward ends of the said straps being extended 45 forwardly as at 5 and adapted to be engaged by a clevis. The side beams 3 are adjustably connected by rods 6 which extend therethrough and have nuts 7 thereon for engaging 50 opposite sides of the beams. By adjusting these nuts on the rods, which rods are screw threaded, the beams 3 can be adjusted toward or from each other as desired. Secured to each of the beams 3 is an apertured 55 cross strip 8. These strips are arranged in pairs, the strips of each pair lapping at

their inner ends and supporting a bearing member 9 which is bolted to them or secured to them in any other preferred manner. By having the strips lapping as described, they 60 can be adjusted relative to each other during the relative adjustment of the beams 3. The bearing members 9 receive the end portions of a longitudinal shaft 10 and secured to this shaft is a hanger 11 having a series of 65 apertures 12, any one of which is adapted to receive the shaft. A set screw 13 is provided whereby the hanger can be securely fastened to the shaft. Each hanger 11 has downwardly diverging arms 14 and the corresponding arms on the two hangers are connected by blades 15 constituting the choppers *per se*. 70

Extending radially from the shaft 10 at a point adjacent the axle 2 are oppositely 75 disposed fingers 16. Cam-shaped tappets 17 are extended radially from the axle 2, these tappets being disposed in pairs, the tappets of each pair being in alignment and disposed at right angles to the tappets of 80 the opposed pair. Furthermore the two pairs of tappets are disposed to engage the respective fingers 16. Thus it will be seen that during the rotation of the axle 2 in one direction, the tappets 17 of one pair 85 will move against and elevate one of the fingers 16, after which a tappet of the other pair will move against and elevate the other finger 16. This operation will be repeated so that during one complete rotation of the 90 axle 2, the hangers 11 will be swung back and forth twice, or, in other words, each blade 15 will have two cutting strokes during one complete rotation of the axle 2.

Ordinary standards 18 may be connected 95 to the front portions of the beams and carry plows of different kinds, as desired, for throwing soil against the plants or for directing it away from the plants. Furthermore, handles 19 may be connected to the 100 rear portions of the beams to facilitate controlling the machine while in operation. As before pointed out, the beams 3 can be adjusted toward or from each other, thus to adapt the machine to rows of different 105 widths. By having the hangers 11 adjustably mounted, the blades 15 can be brought to any desired positions relative to the surface of the ground. Inasmuch as the strips 4 are flexible to a limited extent, it will be 110 apparent that they will not interfere with the lateral adjustment of the machine.

What is claimed is:—

A cotton chopper including a wheel supported revoluble axle, longitudinal beams adjustably connected to and supported by the axle, adjustably connected cross strips carried by the beams, a longitudinal shaft journaled upon said strips, hangers adjustably connected to and movable with the shaft, said hangers having downwardly diverging arms, chopping blades connected to the arms, said blades being parallel with the shaft, oppositely extending fingers connected to and movable with the shaft, and radially disposed tappets revoluble with the

axle and disposed in pairs, the tappets of each pair being adapted to engage and actuate one finger and the tappets of the other pair being adapted to engage and actuate the other finger, said tappets engaging the fingers successively.

In testimony that I claim the foregoing as my own, I have hereto affixed my signature in the presence of two witnesses.

MARTIN M. PERKINS.
